CENTRALIZED TRAFFIC CONTROLLING
SYSTEM FOR RAILROADS**Thomas J. Judge, Rochester, N. Y., assignor to
General Railway Signal Company, Rochester,
N. Y.**

Application March 24, 1933, Serial No. 662,542

14 Claims. (Cl. 246—3)

This invention relates to signalling systems and more particularly to a signalling system for audibly indicating the occurrence of certain conditions in a centralized traffic controlling system 5 for railroads.

In centralized traffic controlling systems it is desirable to indicate by audible means in the central or control office the entrance of trains in certain track sections, so that the operator may 10 have his attention called to train movements when he is engaged in other duties. The control office in such systems has a number of electro-responsive devices or relays, each of which is positioned in accordance with the occupancy of 15 the associated track section and consequently the provision of individual means associated with each such relay for controlling an audible indication device results in considerable apparatus.

In view of the above and other considerations, 20 the present invention contemplates the use of certain common apparatus, cooperating with any number of the above mentioned relays for controlling the audible indication, which results in a considerable reduction in apparatus. It is 25 further proposed to actuate a common audible signal, such as a single stroke bell, once during a cycle of operations when one or more of the relays have been conditioned during the cycle to a position which requires that the audible signal be actuated. The energization of the common signal 30 is preferably effected at the end of an operating cycle, during which indications responsive to particular changes at a remote point are transmitted.

Other objects and advantages of the present 35 invention will be hereinafter set forth in the specification and claims and shown in the drawing. The characteristic features will be explained more in detail in the following description of one embodiment of the invention, while 40 the various advantages of the system will be in part pointed out and in part apparent as the description progresses.

The present audible indication system is shown 45 in the drawing and described in the specification as applied to a selective type of centralized traffic controlling system, such as is shown in the application of N. D. Preston et al., Ser. No. 455,304, filed May 24, 1930, corresponding to Australian Patent 1,501 of 1931. The detailed system to 50 which this invention is applied is not shown or described in the present disclosure, since the operation may be exactly the same as disclosed and thoroughly explained in the above mentioned application. Briefly, the particular functions of 55 the system with which this invention is con-

cerned consists in transmitting a particular combination of impulses from a field station to the control office, for registering the field station in the office and thereafter registering in the control office the condition of the various traffic controlling devices at the field station. 5

The registration of a particular field station in the control office is accomplished by energizing a station relay associated with the transmitting field station such as relay C² or relay C³ in the 10 accompanying drawing, which relays correspond to relays C² and C³ in the above mentioned prior application. After the particular station or track location has been thus registered in the control office, the following impulse or impulses are effective to indicate what the particular change in 15 condition has been, for example, whether the track section has become occupied or unoccupied.

Each of the above mentioned stations which 20 may be registered in the control office has one or more indication storing relays such as relays IN¹, IN² and IN³, which relays correspond to similarly characterized relays in the above mentioned application. Relays IN⁴ and IN⁵ are conditioned by 25 another station, for example station No. 2 with which relay C² is associated. These indication storing relays are illustrated as being of the two-position magnetic stick type, which means that such a relay is arranged to magnetically retain 30 its armature in its last operated position until the application of energy of a reversed polarity from that which positioned it to its last operated position.

A common group of message storing relays MS¹, 35 MS² and MS³ is provided. These relays are of the same type as the IN relays above mentioned, the number required being determined by the maximum number of indication storing relays associated with any one station or location in the system. For example, assuming that relay C³ is the 40 station relay corresponding to station No. 3 and that this station requires three indication storing relays IN¹, IN² and IN³ to register certain indication conditions occurring at the associated station requiring an audible indication. If there 45 is no other station in the system with more than three such indication storing relays, then the total number of message storing relays required is three as shown in the drawing. It will be understood that these message storing relays are used in common, irrespective of the number of stations and the total number of indication storing relays 50 in the control office.

Audible indication control relays AU¹, AU² and AU³ are associated with corresponding message 55

storing relays and are for the purpose of checking the positions of the indication storing relays, as will be later described. The total number of audible indication control relays is the 5 same as the number of message storing relays and it will be understood that these control relays are likewise used in common by all the indication storing relays.

Message recording relay MR repeats the 10 operation of the SAP relay, being picked up at the beginning of a cycle and dropped at the end of a cycle. Relays SA and SAP are the line repeating relays provided in a centralized traffic controlling system to define the bounds of an operating 15 cycle, that is, relays SA and SAP are picked up at the beginning of the cycle and are dropped at the end of a cycle. The detailed circuit arrangement of these slow acting relays is not shown since it may be exactly the same as disclosed 20 in the prior application of T. J. Judge, Ser. No. 652,176 filed January 17, 1933. The bell indicated in the drawing is preferably of the single stroke type although it will be understood that a vibrating type bell can be used if 25 desired.

All of the circuits in the accompanying drawing are shown in their de-energized conditions. It will be understood that the indication storing relays IN¹, IN², IN³, IN⁴ and IN⁵ ordinarily 30 have polar contacts in addition to those indicated in the drawing, which are used for the purpose of energizing visual indication devices such as lamps or the like. The symbols (+) and (-) indicate the positive and negative terminals 35 respectively of suitable batteries or other sources of current and the circuits with which these symbols are used always have current flowing in the same direction. The symbols (B+) and (B-) are employed to indicate the positive and negative terminals respectively of a suitable battery or other source of current having an intermediate tap (CN) and the circuits with which 40 these symbols are used may have current flowing in one direction or the other, depending upon whether the terminal (B+) or (B-) is used in 45 combination with the intermediate tap (CN).

It will now be assumed that a train leaves an occupied track section at station No. 3 and that an operating cycle of the centralized traffic controlling system is initiated as a result. It will be assumed that the indication storing relays 50 IN¹, IN² and IN³ are in the positions indicated in the drawing and that the coded impulses transmitted during the cycle are effective to energize indication buses 16, 17 and 18 with impulses of (-) potential, which energize the three indication storing relays in such a direction that their polar contacts remain in the left hand positions. Buses 16, 17 and 18 are selected and 55 im- 60 pulsed in rotation during the cycle in a manner which is completely disclosed in the above mentioned application Ser. No. 455,304.

When relay SAP is picked up at the beginning of the cycle, a circuit is closed for energizing relay MR which extends from (+), winding of relay MR and front contact 4 of relay SAP, to (-). The picking up of relay MR connects relays MS¹, MS² and MS³ to buses 16, 17 and 18 by way of front contacts 5, 6 and 7 of relay MR. 65 The (-) impulses which are applied to buses 16, 17 and 18 in sequence for positioning relays IN¹, IN² and IN³ to the left are likewise effective to so energize the three message storing relays that their polar contacts remain in the 70 left hand positions.

With all indication storing relay contacts positioned to the left there is no circuit completed for energizing an audible indication control relay such as AU¹, AU² and AU³ and since none of the message storing relays are positioned to the right, the bell circuit is not energized. Only one station relay can be up at the same time, therefore relay C² is down so that relays IN⁴ and IN⁵ are not energized. 5

It will now be assumed that a train enters 10 an unoccupied track section at station No. 3 resulting in an operating cycle of the traffic controlling cycle being effected to register this station in the control office by picking up relay C³. It will be assumed that relay IN¹ is energized 15 with an impulse of (+) potential to record the condition that the unoccupied track section is being entered. This (+) impulse extends through front contact 8 of relay C³ and the winding of relay IN¹, to (CN) and also through front contact 5 of relay MR and the winding of relay MS¹, to (CN), so that relays IN¹ and MS¹ are both positioned to the right. Relay IN¹ closes a circuit for energizing bell wire 10 20 which extends from (+), contact 11 of relay IN¹ in its right hand dotted position, front contact 12 of relay C³, audible indication bus No. 1, contact 13 of relay MS¹ in its right hand dotted position, back contact 14 of relay AU¹ and conductor 10 to the left hand terminal of the bell. 25 Since relay SA is picked up at this time, the other terminal of the bell winding is open at back contact 15 of relay SA. 30

At the end of the cycle, relay SA drops and completes the energizing circuit for the bell through its back contact 15 and front contact 4 of relay SAP, to (-). Shortly after the dropping of relay SA, relay SAP is dropped, because its energizing circuit is open at front contact 19 of relay SA, which in turn de-energizes the bell 35 circuit by the dropping of front contact 4 of relay SAP. The dropping of front contact 4 of relay SAP likewise de-energizes relay MR. The dropping of contact 5 of relay MR closes an 40 energizing circuit for relay MS¹ extending from (CN), winding of relay MS¹, back contact 5 of relay MR and contact 9 of relay MS¹ in its right hand dotted position, to (B-). The current flow 45 in this circuit is of such a direction that relay MS¹ restores its contacts to the left, after which 50 its energizing circuit is opened at contact 9. Similar restoring circuits are completed through back contacts 6 and 7 of relay MR, effective at 55 the end of a cycle to restore relay MS² and/or relay MS³ if picked up during the cycle.

In the event that relay IN² shifts from left to right during a cycle, the bell is energized over a circuit partially made up when the relay shifts its contacts, which extends from (+), contact 20 of relay IN² in its right hand dotted position, front contact 21 of relay C³, audible indication bus No. 2, contact 22 of relay MS² in its right hand dotted position and back contact 23 of relay AU² to conductor 10. At the end of the cycle when relay SA is dropped and before relay SAP releases, the circuit including the bell is completed through back contact 15 of relay SA and front contact 4 of relay SAP, to (-). It will be understood that relay MS² is positioned to the right in this case when indication bus 17 is energized for 60 positioning relay IN² to the right. 65

In the event that relays IN³ and MS³ are positioned to the right during a cycle, then the bell is energized over a circuit partially made up when relay IN³ shifts its contacts, which circuit extends 70 75

from (+), contact 24 of relay IN³ in its right hand dotted position, front contact 25 of relay C³, audible indication bus No. 3, contact 26 of relay MS³ in its right hand dotted position, back 5 contact 27 of relay AU³ and conductor 10 to the left hand terminal of the bell. At the end of the cycle the dropping of relay SA completes the energizing circuit for the bell and it is de-energized when relay SAP drops as previously described.

10 It may happen that an indication storing relay such as relay IN¹ is left in its right hand dotted position from the previous cycle and during the next cycle it may or may not be shifted to its left hand position. In this event it is not 15 required that the bell be energized, first because relay IN¹, if not energized, is an indication that there is no change in the associated track section and second, this relay shifting from right to left is an indication that the associated track section 20 is changing from an occupied to an unoccupied position and does not require the transmission of an audible indication.

With relay IN¹ in its right hand dotted position when relay C³ picks up to register the station 25 in the control office, a circuit is closed for picking up relay AU¹ which extends from (+), contact 11 of relay IN¹ in its right hand dotted position, front contact 12 of relay C³, audible indication bus No. 1, contact 13 of relay MS¹ in its 30 left hand position and upper winding of relay AU¹, to (-). Relay AU¹ closes a stick circuit for itself which extends from (+), lower winding and front contact 28 of relay AU¹ and front contact 4 of relay SAP, to (-).

35 The picking up of relay AU¹ disconnects conductor 10 from contact 13 of relay MS¹ so that the bell circuit is not energized, although relay IN¹ is in its right hand position. At the end of the cycle, the dropping of relay SAP de-energizes the stick circuit of relay AU¹ and it is released. From this typical example it will be apparent that 40 relays AU² and AU³ are picked up and stuck up during a cycle if the corresponding indication storing relays IN² and IN³ are in their right hand dotted positions when relay C³ is picked up. Likewise 45 relays AU¹ and AU² are picked up and stuck up during a cycle if relays IN⁴ and IN⁵ are in their right hand dotted positions when relay C² is picked up. The picking up of these AU relays disconnects conductor 10 from the corresponding 50 polar contacts 13, 22 and 26 of relays MS¹, MS² and MS³ so that the bell circuit is not energized.

From the above description it will be noted that a test is made of the positions of the indication 55 storing relay contacts when a station relay is picked up. If these contacts are in their left hand positions, then the corresponding AU relays are not picked up but if they are in their right hand dotted positions, then the corresponding AU relays are picked up and stuck up until the end of the cycle. The picking up of an AU 60 relay disables the bell circuit which is controlled through contacts of the corresponding indication storing relay, so that the bell cannot be energized during a cycle if the test shows that the indication 65 storing relay is in its right hand position, instead of being shifted from its left hand position to its right hand position.

It will be noted that the positioning of relay 70 IN¹ to its right hand dotted position is effected at the same time that relay MS¹ is positioned to the right. To avoid the picking up of relay AU¹ when contact 11 of relay IN¹ is closed (if this contact closes before contact 13 of relay MS¹ is opened) it is planned to make the audible indica-

tion control relays slow to pick up by any well known means, such as weighted armatures, copper sleeves on the cores or the like.

An audible signal system has thus been provided in which common means are responsive to a change in condition of any one of a large number of indicating relays and it is further provided that the audible signal is only effective when the changed indication is of a certain distinctive nature. The present invention further provides a 10 signal control means which is operable to give only a momentary signal at a particular portion of the transmitting cycle, after which the signal controlling means becomes sensitive to a succeeding change requiring an audible indication. 15

Although the invention has been shown and described more particularly with reference to actuating an audible signal by means of apparatus which is common to a plurality of individual control relays, it is contemplated that the invention will have other uses. For example, the stylus positioning and operating coils in an automatic train recorder may be energized in the manner discussed in connection with the energization of the bell. Since such a recorder serves to register a plurality of indications which occur one at a time, it is obvious that the present circuit arrangement can be used for repeating momentary impulses to the common recorder without the addition of any individual relays to the usual number of indication relays, all of which results in a considerable saving in equipment. 20 25 30

The above rather specific description of one form of the present invention is given solely by way of example and is not intended in any manner in a limiting sense. It is also to be understood that various modifications may be made in order to meet the various individual problems encountered in practice and that the system may 35 be varied in the number of individual and common relays, all without in any manner departing from the spirit or scope of the present invention except as limited by the appended claims. 40 45

What I claim is:—

1. A signalling system for indicating a change in the condition of any one of a plurality of devices, comprising a control relay, contacts operated by each of said devices for establishing a 50 pick-up circuit for said control relay, an energizing circuit for said devices, a storing relay common to a plurality of said devices, means for simultaneously operating any one of said devices and said storing relay over said energizing circuit and means controlled by said storing relay for rendering all of said contacts ineffective to establish said pick-up circuit. 55

2. In a signalling system for railway traffic controlling systems, an audible signal, an energizing circuit for said signal, a plurality of indication relays associated with various track sections, a remotely controlled message relay selectively positioned in synchronism with the positioning of any one of said indication relays, a 60 control relay, a pick-up circuit for said control relay including contacts on any one of said indication relays, and means for preventing the operation of said control relay when one of said indication relays and said message relay are positioned into correspondence at substantially the same time whereby said energizing circuit is rendered effective. 65

3. In a signalling system for railway traffic controlling systems, an audible signal, an energiz- 70 75

ing circuit for said signal, a plurality of indication relays associated with various track sections, a remotely controlled message relay selectively positioned in synchronism with the positioning of any one of said indication relays, a control relay, a pick-up circuit for said control relay including contacts on any one of said indication relays, and means for operating said control relay when one of said indication relays is out of correspondence with said message relay whereby said energizing circuit is rendered ineffective.

4. In combination, a plurality of indication relays capable of being operated only one at a time, a contact on each of said indication relays, a control relay and a message relay common to said indication relays, a single circuit over which any of said indication relays and said message relay are simultaneously energized and signal means jointly governed by said control relay, said message relay and the contact of any one of said indication relays.

5. In combination, a signal, a plurality of indication relays each having a contact, means assuring the operation of only one of said indication relays at any one time, a control relay, a message relay having a contact actuated to first and second positions, an energizing circuit for said control relay including a contact of one of said indication relays and the contact of said message relay in its first position, and means governed by said control relay for selectively operating said signal.

6. In combination, a signal, a plurality of indication relays each having a contact, means assuring the operation of only one of said indication relays at any one time, a control relay, a message relay having a contact actuated to first and second positions, an energizing circuit for said control relay including a contact of one of said indication relays and the contact of said message relay in its first position, and means governed by said control relay for selectively operating said signal including the contact of said message relay in its second position.

45 7. In combination, a plurality of indication relays capable of being operated only one at a time, a contact on each of said indication relays, a control relay and a message relay common to said indication relays, a single circuit over which any one of said indication relays and said message relay are simultaneously energized, an energizing circuit for said control relay including contacts of said message relay and contacts of any of said indication relays, and signal means jointly governed by said control relay, said message relay and the contact of any one of said indication relays.

8. In a signalling system for indicating a change in the condition of any one of a plurality of devices, comprising a control relay, a contact operated by each of said devices, a pick up circuit for said control relay including either one of said contacts, a characteristically energized bus, means for selectively connecting said bus to said devices whereby said devices are operated, and means controlled in accordance with the distinctive character of energization of said bus for rendering said pick up circuit ineffective to energize said control relay.

70 9. In a signalling system, a first plurality of buses selectively and distinctively energized, a plurality of indication storing relays, means for selectively associating said indication storing relays with said first plurality of buses, means responsive to the distinctive energization of said

first plurality of buses for distinctively operating said indication storing relays, a second plurality of buses, means responsive to a distinctive operation of said indication storing relays for energizing said second plurality of buses, an indication signal, means responsive to a distinctive energization of one of said first plurality of buses for effecting the connection of said signal to one of said second plurality of buses, and means responsive to the energization of said one of said second plurality of buses for energizing said signal.

10. In a signalling system, a first plurality of buses selectively and distinctively energized, a plurality of indication storing relays, means for selectively associating said indication storing relays with said first plurality of buses, means responsive to the distinctive energization of said first plurality of buses for distinctively operating said indication storing relays, a second plurality of buses, means responsive to a distinctive operation of said indication storing relays for energizing said second plurality of buses, an indication signal, and means responsive to a distinctive energization of one of said first plurality of buses for preventing the connection of said signal to one of said second plurality of buses whereby the energization of said one of said second plurality of buses fails to energize said signal.

11. In a signalling system, a first plurality of buses selectively and distinctively energized, a plurality of indication storing relays, means for selectively associating said indication storing relays with said first plurality of buses, means responsive to the distinctive energization of said first plurality of buses for distinctively operating said indication storing relays, a second plurality of buses, means responsive to a distinctive operation of said indication storing relays for energizing said second plurality of buses, an indication signal, means responsive to a first distinctive energization of one of said first plurality of buses for effecting the connection of said signal to one of said second plurality of buses, means responsive to the energization of said one of said second plurality of buses for energizing said signal, and means responsive to a second distinctive energization of one of said first plurality of buses for preventing the connection of said signal to one of said second plurality of buses whereby the energization of said one of said second plurality of buses fails to energize said signal.

12. In a signalling system for indicating a change in the condition of any one of a plurality of devices, comprising a control relay, a contact operated by each of said devices, a pick-up circuit for said control relay including either one of said contacts, an energized bus, means for selectively connecting said bus to said devices whereby said devices are operated, and means controlled by the energized condition of said bus for rendering said pick-up circuit ineffective to control said control relay.

13. In a signalling system for indicating a change in the condition of any one of a plurality of devices, comprising a control relay, a contact operated by each of said devices, a pick-up circuit for said control relay including either one of said contacts, an energized bus, means for selectively connecting said bus to said devices whereby said devices are operated, means controlled by the energized condition of said bus for rendering said pick-up circuit ineffective to con-

trol said control relay, and signalling means controlled by said control relay.

14. In a signalling system for indicating only one of a plurality of changes in the condition of any one of a plurality of devices, comprising a control relay, a contact operated by each of said devices, a pick-up circuit for said control relay including either one of said contacts, an

energized bus, means for selectively connecting said bus to said devices whereby said devices are operated, means controlled by the energized condition of said bus for rendering said pick-up circuit ineffective to control said control relay, and 5 signalling means controlled by said control relay.

THOMAS J. JUDGE.
